DESK

William James Bargen, Waukegan, Ill.

Application May 20, 1947, Serial No. 749,288

2 Claims. (Cl. 311—1)

1

This invention relates to a desk assembly.

An object of this invention is to provide a desk assembly embodying a main desk unit, and one or more abutting units which are adapted to be locked to the main desk unit by means of rubber shoes.

Another object of this invention is to provide an improved main or center desk unit having a single supporting pedestal or standard which is substantially I-shape in horizontal section, and formed of molded plywood, metal or plastic.

A further object of this invention is to provide a center desk unit which may be coupled to one or more drawer units, a typewriter desk unit and a drawer unit, or any selected combination of added units so as to provide a desk assembly of predetermined size and capacity.

A further object of this invention is to provide a center or main desk unit which in one form of the invention is of sector-shape so that the added units will be radially disposed with respect to the rear side of the center desk unit.

A further object of this invention is to provide a center or main desk unit wherein the top thereof is rectangular in configuration so that the added desk units will be in alignment.

A further object of this invention is to provide an improved drawer unit as an additive unit for a main desk unit which embodies an improved drawer construction.

A further object of this invention is to provide an improved drawer unit embodying a streamlined drawer front, and means for securing the front to the front wall of the drawer so that the unit will be attractive in appearance.

A further object of this invention is to provide an improved drawer construction which is formed of confronting U-shaped molded plywood members and interposed blocks so that drawers of any width may be formed from standard U-shaped members.

A further object of this invention is to provide desk construction for either a typewriter or drawer desk unit wherein the body of the desk is of U-shape in horizontal section, being formed of a U-shaped front wall, and parallel side walls secured at their forward edges to the rear edges of the legs of the front wall so as to provide a unitary construction which is formed out of plywood. The desk is supported by means of short legs integral with the side wall structure, and the legs are adapted to have rubber shoes thereon to resist sliding movement on a polished floor.

A further object of this invention is to pro-

2

vide a desk construction which embodies a minimum of joints between the walls thereof so that the desk will be strong and at the same time will be of attractive appearance.

A further object of this invention is to provide a desk construction having a unitary U-shaped body frame formed of molded plywood, the frame forming at least three walls of the desk which will provide rigid support for the top, and for the drawers or other parts which may be secured within the body. The frame is supported above a floor by means of short legs which may be integral with certain walls of the frame and the legs may have cushion shoes thereon for preventing undue sliding or scratching of polished floors.

With the above and other objects in view, my invention consists in the arrangement, combination and details of construction disclosed in the drawings and specification, and then more particularly pointed out in the appended claims.

In the drawings,

Figure 1 is a plan view of a desk assembly constructed according to an embodiment of this invention,

Figure 2 is a detail rear elevation of the assembly,

Figure 3 is a bottom plan of a modified form of the center desk unit,

Figure 4 is a fragmentary sectional view taken on the line 4—4 of Figure 4,

Figure 5 is a fragmentary sectional view taken on the line 5—5 of Figure 4,

Figure 6 is a fragmentary sectional view taken on the line 6—6 of Figure 1,

Figure 7 is a diagrammatic view showing a modified form of desk assembly,

Figure 8 is a diagrammatic view of another modified form of desk assembly,

Figure 9 is a diagrammatic view of another modified form of desk assembly,

Figure 10 is a diagrammatic view of another modified form of desk assembly,

Figure 11 is a diagrammatic view of a further modified form of desk assembly,

Figure 12 is a diagrammatic view of a further modified form of desk assembly,

Figure 13 is a diagrammatic view of a further modified form of desk assembly,

50 Figure 14 is a bottom plan view of the sector-shaped main or central desk unit.

Referring to the drawings, and first to Figures 1 and 2, the numeral 30 designates generally a center desk unit which includes a pedestal or standard 31, having a top 32 secured thereto.

The top 32, as shown in Figure 1, is of sector-shape, being formed with straight radially disposed side edges 33, a convex outer edge 34, and a concave inner edge 35. The pedestal or standard 31, as shown more clearly in Figure 8, is formed of an arcuate central portion 36 formed of plywood and disposed in a vertical position, which has extending from the opposite vertical edges thereof of arcuate extensions 39.

The arcuate extensions 39 are disposed in forwardly extending position, diverging outwardly and these extensions 39 have secured thereto vertical plywood columns or legs 40. The columns or legs 40 are secured to the outer ends of the extensions 39 by means of an overlapping or rabbeted joint, as at 41. The legs or columns 40 extend below the extensions 39, as shown more clearly in Figure 4, and provide feet 42 for supporting the standard or pedestal in upwardly spaced relation to the floor.

The standard member 36 also includes a pair of rearwardly extending curved extensions 37, disposed in face abutting relation at their inner portions to the straight central inner portions of the front extensions 39, and secured to the latter by means of dowels 38, and the inner ends of the curved extensions 37 and 39 are formed with tongues 43 and 44, respectively, which are glued into a vertical groove 45 formed in the outer edge of the center section 36. Rear legs or columns 46 are connected to the rear edges of the extensions 37 by an overlapping or rabbeted joint 47. The lower ends of the legs or columns 46 extend below the lower edges of the rear members 37 so as to provide supporting feet 48 similar to the feet 42.

Referring now to Figure 6, the central portion 36 of the pedestal or standard 31 is secured to the lower side of the top 32 by means of dowels 49. The legs carried by the pedestal 31 are also adapted to be secured to the top 32 by means of dowels 50, as shown in Figure 5.

Referring now to Figure 3, there is disclosed a modified form of center desk unit generally designated as 52. This unit 52 is formed of a rectangular top 53 which is secured to a pedestal or standard generally designated as 54. The standard 54 is formed of a central straight member 51, a forwardly extending pair of arcuate extensions 56, and a rearwardly extending pair of extensions 57. The forward edges of the extensions 56 have fixed thereto supporting legs or columns 58 and the rear edges of the rear extensions 57 have fixed thereto supporting legs or columns 60. The legs 58 and 60 are secured to the extensions 56 and 57 in the same manner as the legs 40 and 46 are secured to the pedestal member 36, as shown in Figure 4.

The desk unit 31 is adapted to have positioned on one side thereof a typewriter desk unit generally designated as 61.

The assembly, shown in Figure 1, also includes a drawer unit generally designated as 73.

With a desk assembly as hereinbefore described, various combinations of these units may be used. One combination is disclosed in Figure 1, wherein the center desk unit 30 has disposed on the opposite sides thereof a typewriter unit 61 and a drawer unit 73. If desired there may be two desk units, such as unit 30 and unit 52 secured together, and on the opposite side of the desk unit 30 there may be mounted and secured together a typewriter unit 61 and a drawer unit 73.

Another arrangement of these units is shown

in Figure 8, wherein the rectangular center desk unit 52 has mounted on the opposite sides thereof a pair of drawer units 73. A further arrangement of desk is shown in Figure 9, wherein the typewriter unit 61 is the center unit and has disposed on the opposite sides thereof a pair of drawer units 73.

In Figure 10, another arrangement is disclosed using the desk unit 52 with the rectangular top and having extending from only one side thereof a typewriter unit 61 with a drawer unit 73 extending from the outer side of the typewriter unit 61.

Another arrangement of desks is shown in Figure 11, using the center sector-shaped unit 30 and a pair of drawer units 73 on the opposite sides thereof.

In Figure 1 there is disclosed a typewriter unit 61 with only one drawer unit 73 extending from one side thereof.

Figure 13 also discloses a further arrangement embodying the two desk units 30 and 52 with a pair of drawer units 73 extending from the outer side of sector unit 30, and the outer side of rectangular unit 52.

The arrangement shown in Figures 7 and 13 merely discloses various desk arrangements which are possible with the separate units herein described. It will, of course, be understood that various other arrangements may be made, depending on the needs of the user.

Each desk unit as hereinbefore described, is formed of molded plywood, having substantial thickness so as to provide a strong supporting pedestal or standard, and the tops of the units may also be formed of plywood of desired thickness. With a desk construction as hereinbefore described, wherein the assembly is formed of separate units connected together by the rubber shoes, the manufacturer will be better able to satisfy the demands of the customer by providing standard units which can be coupled together in any desired manner to provide the necessary desk assembly.

I do not mean to confine myself to the exact details of construction herein disclosed, but claim all variations falling within the purview of the appended claims.

What I claim is:

1. In a desk construction a standard and a desk top of sector shape having a convex outer edge, a concave inner edge conforming to the curvature of said outer edge and straight side edges, said standard including an arcuate central panel conforming to the curvature of said outer and inner edges extending transversely beneath said top and positioned intermediately between said outer and inner edges, arcuate members interlocked with the end of said panel diverging forwardly and rearwardly in opposite directions from each end thereof and front and rear leg portions elongated in transverse section interlocked with the divergent ends of each member extending longitudinally along said side edges, said top and said standard being comprised of laminations of integrally formed moulded plywood.

2. In a desk construction a standard and a desk top, said standard including a central panel extending transversely beneath said top and positioned intermediately between the outer and inner edges of the top of the desk, arcuate members interlocked with the end of said panel diverging forwardly and rearwardly in opposite directions from each end thereof and front and

rear leg portions elongated in transverse section interlocked with the divergent ends of each member extending longitudinally along the side edges of said top, said top and said standard being comprised of laminations of integrally formed molded plywood.

WILLIAM JAMES BARGEN.
